DOOR CATCH

Alden E. Hammerbeck, Duluth, Minn., assignor of
two-fifths to E. E. Webber, Duluth, Minn.

Application May 22, 1937, Serial No. 144,225

3 Claims. (Cl. 16—65)

This invention relates to door controlling means, the principal object being to provide a more simple and efficient device of this character, and other novel features and advantages of the invention will appear in the following description thereof.

Referring now to the accompanying drawing, forming part of this application, and wherein like reference characters indicate like parts:

10 Figure 1 is a perspective view of the upper portion of a door to which the device is applied near the hinged edge of the door, it being in constant contact with the door.

15 Figure 2 is a perspective view of the catch unit only of the device.

Figure 3 is a perspective view of the catch applied to the frame of the door and a modified attachment upon the door intermittently engaged by the catch.

20 Figure 4 is a perspective view of the arrangement shown in Figure 3 of the drawing when the door is closed and held by the catch.

The catch proper, as more clearly illustrated in Figure 2 of the drawing, comprises a housing 1, made either of cast or sheet metal, as desired, having inwardly turned lips 2 thereupon adjacent one end. These lips are for the purpose of tightly holding a substantially flat sheet metal spring 3 at one end, the opposite end of which is 25 in constant engagement with the flattened side 4 of the supporting cross member 5 of the swingable yoke 6 carrying upon its forward cross member the rubber or other like roller 7, and which action of the spring 3 against the flattened portion 4 tends to hold the yoke and roller inwardly towards the body portion almost at right angles to the back of the housing.

When the catch is installed upon the frame of the door, as shown in Figure 3, the free end 40 of the spring 3 will engage the bar 5 to one side of the flattened portion 4 and hold the yoke and roller substantially parallel with the back of the catch housing, as clearly illustrated. In this installation a hook shaped flat metal clip, illustrated at 8, is installed upon the edge of the door 45 9 in such a manner that the outwardly turned lip 10 of the clip 8 will just clear the roller 7 in passing same when the door is closing, the roller 7 engaging the bracket portion 11 of the clip on the door.

If the door thus equipped is swung forwardly with the ordinary motion of a door closing, this engagement of the roller against the bracket portion of the clip will tend to swing it slightly inwardly of the clip, which will bring the flattened

portion 4 of the bar 5 of the yoke into cooperative engagement with the free end of the spring 3, and being thus instantly effected by the force of the spring, will tend to swing the yoke and roller into the position shown in Figure 2 of the drawing, thus drawing the door by such engagement of the roller 7 with the clip 8 into the position clearly shown in Figure 4 of the drawing, when the yoke, still biased by the action of the spring 3, will hold the door tightly closed, thereby providing an extremely simple door catch.

In Figure 1, the housing of the catch is illustrated at 12 and is arranged near the hinged edge of the door, it being of identical construction with that just described. In this instance, 15 however, there is but one outwardly extending arm indicated at 13 the portion of this arm indicated at 14 which extends within the housing is identical with the cross member 5 of the yoke 6, and is provided with a flattened area 15 engaged by a spring identical with that shown in Fig. 2 of the drawing. The extreme outer end of the arm 13 is looped as at 16 and is slidably mounted upon the elongated wire bracket 17 attached to the door 18, preferably near the uppermost extremity thereof, so that when the door is swung toward closed position, sufficient for the flattened portion 15 of the cross member 14 to be engaged by the free end of the spring 20 within the catch, it will tend to draw the door 25 closed and tightly hold same in such position, it being obvious that this is simply a modified application of the catch to the door.

It should be borne in mind that this device is more particularly adapted for use on a screen or light storm door, where such a device is particularly desired, though it is obvious that the same may be very effectively used on cabinet, medicine chest, or other light doors.

Having thus described my invention, what I 40 claim and desire to secure by Letters Patent, is:

1. A door catch comprising a housing adapted to be secured to a door frame, a leaf spring secured within said housing adjacent one wall thereof, a unitary arm having a flattened end 45 extending within said housing between the spring and said wall whereby said arm is biased toward the limit of its movement in one direction, a bracket adapted to be secured to the door and in the path of said arm, and means on the free end of said arm for engagement with the bracket on the door.

2. A door catch comprising in combination a housing adapted for attachment to a door frame, a link shaped arm pivotally installed at one end 55

within and transverse one end of said housing, a roller pivotally carried upon the opposite end of said arm, a spring fixed within said housing and engaging a flattened portion of said arm there-
5 within whereby to bias said arm toward the limit of its movement in one direction, and an articu-
ately shaped catching member on said door for
engagement with said roller when said arm is
disposed toward said door opening and the door
10 is in the act of closing and which engagement,
if normal, will throw said arm toward its biased
position and hold the roller engaged within said
catching member and the door closed.

3. A door catch of the character described in-

cluding a housing adapted to be installed upon
the frame of the door, a leaf spring within said
housing and adjacent one wall thereof, a door
engaging member having a flattened end ex-
tending within the housing between said spring
and said wall whereby said member is biased
in one position, means upon the door for co-
operative engagement with the free end of said
member whereby the action of the door will throw
said lever past the neutral point intermediate of
the limits of its movement simultaneously with
holding engagement of said means with said
member and thus hold the door in closed position.
